UNITED STATES PATENT OFFICE.

PHILIP SHAFTER, OF MANHATTAN BEACH, NEW YORK.

OUTER GARMENT OR SWEATER.

Application filed June 27, 1924. Serial No. 722,831.

To all whom it may concern:

Be it known that I, PHILIP SHAFTER, a citizen of the United States, residing at 75 Amherst Street, Manhattan Beach, in the county of Kings and State of New York, have invented certain new and useful Improvements in Outer Garments or Sweaters, of which the following is a specification.

This invention relates to improvements 10 in wearing apparel and has particular reference to outer garments such as sweaters, sweater coats, or other knitted garments of like character.

More specifically, my invention relates 15 to the provision of an auxiliary collar for such garments and in combination therewith and adjacent thereto a pair of reversible lapels.

The object of my invention is to produce 20 a garment which can be used either as a sweater with the usual V-shaped neck opening or as a sweater having a collar and lapels. As a further alternative, it is my object to provide a pair of lapels so arranged with reference to said garment and the collar there- 25 of that they may be worn turned back in the usual manner or folded over each other to close said V-shaped opening more or less and thereby protect the chest of the 30 wearer in cold weather when desired.

My improvement provides a three-in-one garment that may be worn with its parts in any of three different relative positions each of which gives a pleasing appearance 35 to the garment.

While I have shown my improvement applied to a knitted sweater, it is broadly applicable to any garment which may be provided with a collar and lapels.

40 In the accompanying drawings:—

Figure 1 shows a sweater adapted to be worn in the usual V-neck style the attached collar and lapels being shown folded inwardly to lie against the body of the user and con- 45 cealed from view.

Fig. 2 shows my improved sweater ar- ranged for a second manner of wear having the auxiliary collar and lapels turned out to appear in the usual manner of the same.

50 Fig. 3 shows the same sweater arranged for a third manner of wear in which the lapels are shown folded over each other.

Figure 4 shows the auxiliary collar and lapels as they appear when spread out in the same plane, the broken lines indicating 30 the position of the lapels when in concealed position.

Referring in detail to the drawing num- 35 eral 1 indicates the body of a sweater coat having a collar band 2 which is ar- ranged to provide the usual V-shaped neck opening 3. Within the coat along the inner lower edge of said band, is attached an aux- 40 iliary collar member 4 which may be made of the same material and color of the coat body or of a different material or color.

As clearly shown in Fig. 4, the auxiliary 45 collar 4 is attached to band 2 along line d d'. Adjacent each end of collar 4, I attach on lines b d and b' d' a lapel member 5. Each lapel 5 is attached along one edge to collar band 2 as shown at a d and a' d'.

Fig. 1 shows the sweater coat in position 50 to be worn in the usual V-neck style. Collar 4 and lapels 5 are shown turned in to be concealed from view in which position these parts lie flat against the body of the wearer and the inner surface of the sweater as shown for the major part by dotted lines.

Fig. 2 shows the sweater arranged for a 55 second manner of wear. Collar 4 and lapels 5 are here shown as turned out to appear in the usual position of such elements.

Fig. 3 shows a third manner in which 60 my improved sweater can be worn wherein 65 lapels 5 are shown as turned inwardly to overlap each other and close that portion of the V-shaped opening which is adjacent 70 the chest of the wearer. As shown in this figure the right hand edge of the outermost 75 lapel when folded is located between the collar band and the rear lapel and underlaps said band. In this position, said lapels cover the chest of the wearer in the vicinity of the V-shaped opening and thereby func- 75 tion to protect the wearer from extreme cold or winds. A button or other fastener 6 is provided at a suitable location on the inner face of band 2 to engage a loop or button hole 7 adjacent the tip of the outer lapel 5.

Fig. 4 shows how collar 4 and lapels 5 appear when the sweater is fully thrown open to bring these parts into the same

plane. With the sweater front closed as in Fig. 1 the lapels will assume the position shown by the broken lines in Fig. 4.

I claim as my invention,—

5 A combination garment having a V-shaped neck opening and a collar band, an auxiliary reversible collar, reversible lapels attached to said reversible collar along a portion of adjacent ends, said reversible col-

lar and lapels being attached to the inner 10 surface of said garment inwardly from the edge of said opening whereby said lapels may be crossed to overlie each other in which position a portion of the outermost lapel will engage between the inner lapel 15 and said collar band.

In testimony whereof I affix my signature.

PHILIP SHAFTER.
